FUEL BOOSTER PUMP

Filed Sept. 3, 1929

UNITED STATES PATENT OFFICE

CLIFFORD C. BRADBURY, OF GLENCOE, ILLINOIS, ASSIGNOR TO CURTIS B. CAMP,
TRUSTEE, OF GLENCOE, ILLINOIS

FUEL BOOSTER PUMP

Application filed September 3, 1929. Serial No. 389,904.

My invention relates to vacuum apparatus and will be described with particular reference to a fuel lifting apparatus for motor vehicles.

5 In climbing steep grades the fuel supply tank of a motor vehicle which is usually located at the rear of the vehicle is much lower with respect to the engine than when the vehicle is on a level road. Many types of 10 fuel lifting devices on the market are not adapted to and are incapable of lifting fuel far enough to supply fuel to the auxiliary supply tank at the engine under these conditions. If the fuel supply in the auxiliary 15 or vacuum tank of the vehicle happens to be low at the foot of a long incline, it is apt to be exhausted before the top of the incline is reached, with the result that the engine will stop for lack of fuel.

20 An object of my invention is to provide a new and improved fuel lifting apparatus.

A further object is to provide an apparatus for producing a high degree of vacuum for lifting fuel in a motor vehicle.

25 A further object is to provide a Venturi type of vacuum device which is closed to the atmosphere preventing the passage of air therethrough until a predetermined suction is reached.

30 A further object is to provide a vacuum device having successive cumulative stages for producing a high vacuum.

Other objects and advantages will appear as the description proceeds.

35 Referring to the drawings;

Fig. 1 is a side elevation illustrating a fuel lifting device embodying my invention;

Fig. 2 is a cross-sectional view of a unit of the vacuum producing device; and

40 Fig. 3 is a section taken on the line 3—3 of Fig. 2.

The invention comprises, in general, a plurality of containers 5, 6 and 7 for storing air under low pressure, each of which has 45 a Venturi tube 8, 9 and 10, respectively, as-

sociated therewith. The first Venturi tube 8 has a tube 13 connected thereto leading to a manifold 15 of the motor, the operation of the motor maintaining a continuous suction in the manifold. The last container 7 50 is connected by a tube 16 to a vacuum tank 17 of the usual construction to which the high vacuum produced by the apparatus is to be communicated.

Each of the Venturi tubes has an internal 55 bore provided with a tapering mouth 21 leading to a restricted throat 22, and rearwardly of the throat the bore is again flared outwardly as at 23. Communicating with the throat is an intake from a container 60 comprising an aperture 24 leading into a valve chamber 25. The valve chamber is adapted to receive a plug 26 threaded into the wall of the Venturi tube and into a boss 20 of the container. The end of the plug is 65 provided with a valve seat for receiving a ball type valve 27 which is resiliently urged to its seat by a spring 28.

Rearwardly of the flared portion 23 the tube is provided with a cylinder 31 having 70 a plunger 32 reciprocably mounted therein. The front face of the plunger is adapted to rest against a shoulder 33 in the tube which may be ground to provide a close fit when the plunger is in its forward position. Immediately adjacent the shoulder is 75 a pair of saw cuts 30 for admitting air to the end of the tube when the plunger is retracted. The plunger and saw cuts thus form a valve at the end of the Venturi tube. The plunger is provided with a hollow bore 34 and its rearward end terminates in a radially outwardly extending flange which forms a piston 35 movably mounted 80 in an enlarged portion of the tube forming a cylinder 36. The plunger is provided with an annular recess and the space surrounding the plunger and forwardly of cylinder 35 is connected to the atmosphere 85 90

by a passage 37 formed in the wall of the tube.

In order to prevent the leakage of air into the cylinder 36 an annular packing ring 38 is placed at the forward end of the cylinder. Extending forwardly from plunger 32 is a tube 41 having a slightly tapering end which extends forwardly of the throat 22 when the plunger is in its forward position in which it is normally maintained by spring 42. In the retracted position of the plunger the end of tube 41 is directly in the throat 22. This tube connects the interior of the Venturi tube with cylinder 36.

Assuming now that the motor is in operation, the manifold suction is communicated through tube 13 to the first Venturi tube 8. The manifold suction is transmitted through tube 41 to cylinder 36 producing a low pressure in the cylinder. The pressure on opposite sides of the plunger is equal at this time but the low pressure in the cylinder on the back face of piston 35 together with atmospheric pressure through passage 37 upon the front face of piston 35, causes the piston to retract as soon as the low pressure is sufficient to overcome the force of spring 42, drawing the plunger 32 with it. As soon as plunger 32 is withdrawn from shoulder 33 air will enter saw cuts 30 and increase the pressure on the forward face of the plunger, causing the plunger to retract with a snap action. Another factor tending to cause the plunger to retract with a snap action is the fact that tube 41 in the forward position of the plunger extends forwardly of the throat of the Venturi tube. When the plunger retracts, the end of tube 41 will be drawn farther into the throat of the Venturi tube and thus increase the suction thereon so that as soon as the plunger begins to retract the conditions produced thereby will move the plunger with considerable speed to its retracted position. The air drawn through the saw cuts 30 passing through the restricted throat of the Venturi tube causes a high suction on the intake of container 5 withdrawing air from this container until the tank reaches a stage of exhaustion equal to the capacity of tube 8.

When the suction on tube 8 by the manifold falls to a predetermined value plunger 32 will again be returned to its forward position with a snap action. This is due to the fact that the forward movement of the plunger causes the end of tube 41 to be moved forwardly of the throat of the Venturi tube and a further movement of the plunger interrupts the passage of air through the saw cuts thus decreasing the pressure on the face of the piston so that as soon as the pressure in the tube falls low enough to allow the plunger to begin

its forward movement other factors immediately tend to accelerate this movement, causing the plunger to move forward with a snap action.

The spring for maintaining the plunger of tube 9 in its forward position is made slightly stronger than the corresponding spring of tube 8. When container 5 reaches a given degree of exhaustion, corresponding to the strength of the spring of tube 9, suction on this tube will cause its plunger to 70 retract and the low pressure in the container 5 which is many times lower than that in the manifold will draw air through tube 9 to produce a high suction on the intake of container 6, boosting the suction in container 6 80 above that of container 5. The air admitted to container 5 through tube 9 will decrease the degree of exhaustion of container 5 and allow the pressure to increase therein. As soon as the exhaustion has decreased to such an extent as to allow the plunger of tube 9 to cut off the flow of air to the container 5, vacuum will again begin to build up in container 5 until the suction therein is sufficient to again operate tube 9.

Thus it will be seen that the exhaustion of container 6 takes place intermittently allowing the vacuum to build up in container 5 and then utilizing that vacuum to produce a higher vacuum in container 6. The exhaustion of container 7 takes place in a similar manner, tube 10 having a spring of such strength as to cause the tube to operate on a higher suction than tube 9. When the vacuum in the container 6 reaches a given value the tube 10 is operated to exhaust the air in container 7, the reduction of pressure in the container 7 taking place intermittently.

Container 7 is connected to vacuum tank 17 in the usual manner, it being customary in some types of fuel lifting devices to connect the tubes 13 directly to the vacuum tank. By the interposition of the vacuum boosting apparatus described any desired degree of vacuum may be obtained to be applied to the vacuum tank.

While three stages for increasing the vacuum of the manifold have been described, it will be understood that it is not necessary in all cases to use three tanks and in other cases it may be desirable to use more. The invention contemplates the use of any number of stages for increasing the vacuum.

Having described the nature and embodiment of my invention, what I desire to secure by United States Letters Patent is as follows:

1. In an apparatus for producing a vacuum, a Venturi tube having a restricted throat, an intake in said throat, a valve controlling the admission of air to the end of said tube, and means for closing said valve when the suction in the tube falls to a pre-

determined value and opening said valve when the suction exceeds said value to govern the withdrawal of air to produce a low pressure in means associated with said tube.

5 2. In an apparatus for producing a vacuum, a Venturi tube having a restricted throat, an intake in said throat, whereby a high suction is produced at the intake by air passing through the tube from the end of the tube, a valve at the end of the tube for

10 controlling the admission of air thereto, means for opening said valve when the suction on the tube reaches a predetermined value, and means for closing said valve when 15 the suction falls below said value to govern the withdrawal of air to produce a low pressure in means associated with said tube.

15 3. In an apparatus for producing a vacuum, a Venturi tube having a restricted throat, an intake in said throat, a valve rearwardly of said throat for admitting air to the end of the tube, a cylinder having a movable piston therein for actuating said valve, said piston being operable in response 20 to the degree of suction in the tube to govern the withdrawal of air to produce a low pressure in means associated with said tube.

25 4. In an apparatus for producing a vacuum, a Venturi tube having a restricted throat, an intake in said throat, a valve at the end of the tube having a movable plunger, said valve having an aperture in a position to be closed in one position of the plunger and open in another position there- 30 of, a cylinder connected with said tube, a piston therein for actuating the plunger of the valve, whereby a high suction in the tube causes the piston to actuate the plunger to open the aperture in the valve and admit air 35 to the end of the tube to govern the withdrawal of air to produce a low pressure in means associated with said tube.

40 5. In an apparatus for producing a vacuum, a Venturi tube having a restricted throat, an intake in said throat whereby a high suction is produced at the intake by air passing through the tube, a passage for admitting air to the end of the tube, a plunger for controlling said passage, a cylinder having a piston therein for actuating the plunger, a tube carried by the plunger for connecting the cylinder to the Venturi tube, said tube extending forwardly of the throat of the Venturi tube when plunger 45 closes said passage and into the throat when the plunger opens said passage.

45 6. In an apparatus for producing a vacuum, a Venturi tube having a restricted throat, an intake in said throat whereby the 50 passage of air through the tube produces a high suction at the intake, a passage for admitting atmospheric air to the tube, a plunger for controlling said passage, means for normally retaining the plunger in a position 55 to close said passage, a cylinder having a

movable piston therein for actuating the plunger, a tube carried by the plunger for connecting the cylinder to the Venturi tube, said tube extending forwardly of the throat of the Venturi tube when the plunger closes 70 said passage and into the throat when the plunger opens said passage, whereby a predetermined suction in the Venturi tube causes a retraction of the plunger to open said passage. 75

7. In an apparatus for producing a vacuum, a Venturi tube having a restricted throat, an intake in said throat, a container connected to said intake and adapted to have air withdrawn therefrom to produce a 80 low pressure therein, a second Venturi tube having a restricted throat and having its mouth connected to said container, an intake in the throat of said second Venturi tube, and means effecting the passage of air 85 through said second tube only when the pressure in the container reaches a predetermined value whereby a lower pressure is produced in the intake of the second Venturi tube than that in the container. 90

8. In an apparatus for producing a vacuum, a Venturi tube having a restricted throat, a valve for admitting air to the end of said tube, an intake in said throat, means for causing the valve at the end of the tube 95 to admit atmospheric air to the tube, means for rendering said last mentioned means ineffective when the suction in the tube falls below a predetermined value, a container connected to said intake and adapted to have 100 air withdrawn therefrom to produce a low pressure therein, a second Venturi tube having a restricted throat and having its mouth connected to said container, an intake in the throat of the second Venturi tube, and 105 means for effecting the passage of air through said second tube only when the pressure in the container reaches a predetermined value whereby a lower pressure is produced in the intake of the second Venturi 110 tube than that in the container.

9. In an apparatus for producing a vacuum, a plurality of containers for storing air under low pressure, a suction device for producing a low pressure in said containers 115 and means interconnecting said containers for transmitting low pressure from one container to a succeeding container whereby each container boosts the vacuum transmitted to the succeeding container. 120

10. In an apparatus for producing a vacuum, a container for storing air under low pressure, a suction device for producing a low pressure in said container, a second container for storing air under low pressure, 125 and means interconnecting said second container with the first container whereby a lower pressure will be produced in the second container than in the first container.

11. In an apparatus for producing a vac- 130

uum, a Venturi tube having a restricted throat, an intake in said throat whereby a high suction is produced at the intake by air passing through the tube, a valve at the 5 end of the tube for admitting air thereto, and means associated with said valve and positioned in said throat for actuating said valve with a snap action in response to the suction within the tube.

10 In witness whereof, I hereunto subscribe my name this 30th day of August, 1929.
